UNITED STATES PATENT OFFICE

JAKOB KLEIN, OF NEW YORK, N. Y., ASSIGNOR OF FIFTY PER CENT TO MAX BACKER,
OF NEW YORK, N. Y.

RAILROAD CROSSING BARRIER

Application filed January 28, 1932. Serial No. 589,329.

The main object of this invention is the provision of a mechanism in combination with a railroad track whereby the gates at a crossing are automatically lowered when an approaching train reaches a predetermined point ahead of the crossing. An audible or visible alarm, or both, may be used in combination with this device, but as both such alarms are common, they are not set forth in this specification.

Another object of the invention is the provision of a mechanism as above-mentioned, with further means for keeping the crossing gates closed until the train has passed the crossing, and for re-opening the gates at the latter time.

The above and other objects will become apparent in the description below, in which characters of reference refer to like-named characters on the drawing.

Referring briefly to the drawing, Figure 1 is a plan view of a track section and a crossing, illustrating the invention.

Figure 2 is a side elevational view of the same.

Figure 3 is an enlarged sectional view taken through one of the drums which winds a cable connected to a gate.

Referring in detail to the drawing, the numeral 10 represents the track rails, and 11 represents a cam-like extension or projection on a locomotive, whose function it is to operate the gate-closing and opening mechanism.

A lever 12 is pivotally mounted at its end 13 to a tie or other suitable means, at a predetermined point along the track, in advance of the crossing. This lever tilts in the direction of travel of the train, and at its upper end is provided with a slightly-curved head 14 which is depressed by the projection 11 when the locomotive passes this head. A rigid arm 15 extends rearward from the lever 12, and a cable 16 is secured in this arm. This cable is trained over a pulley 17, and at its other end a weight 18 is supported in suspension. This weight 18 must necessarily be heavy, but in order to simplify the illustration, it has been shown relatively small. A wall 19 provided with a vertical groove 20 extends adjacent this weight, the weight be-

ing vertically slidable in the groove. A band 21, secured to the wall 19 about the weight, constrains the weight to movement along the groove.

An ear 22 extends integrally from the forward side of the lever 12, and in this ear the ends of two cables, 23 and 24, are secured. Each gate 26 extends rigidly from a drum 25 rotatably supported in uprights 27 on opposite sides of the crossing. The cables 23 are secured to the peripheries of the drum in any suitable manner, such as by a pin 28 as shown in Figure 3. A spring 29 is located between the weight 18 and the weight end of cable 16, in order to take up shock when the cable is suddenly tensed.

Opposite the weight 18, below the track level, a wall 30 and a floor 31 are formed. A horizontal bracket 32 extends rigidly from this wall, and in its end a link 33 is pivotally supported. A spring 34 normally draws the upper end of the link 33 toward the wall 30. A horizontal bar 35, having a roller 36 in its end, is slidably mounted on the floor 31, and a sleeve 37, attached to the floor, constrains this bar to longitudinal motion. This bar 35 is pivotally connected to the lower end of the link 33. Connected pivotally to the upper end of the link 33, is a long horizontal bar 38 which extends along the track to a point some distance the other side of the crossing. At its far end said bar is pivotally connected to the lower end of forwardly-tilted lever 39 pivotally mounted intermediate its length to a tie or other means. A wall 40 is provided adjacent the lever 39, and a spring 41 secured to the wall and the lever 39 normally pulls the lower end of the lever toward the wall. The upper end of the lever is provided with a slightly-curved head 42, as shown.

The operation of the device is as follows. Normally the gates are raised, as shown in broken lines in Figure 2, and the cables 23 and 24 are taut between the drums 25 and the ear 22. Since the amount of rotation of the drums required to loosen the cables sufficiently to enable the gates to drop to horizontal or closed position, is less than a quadrant, it is obvious that lessening the length of cable 100

between roller 43 and ear 22, or roller 44 and ear 22, only a short distance, will enable the gates to fall of their own weight. The projection 11 on the locomotive causes depression of head 14 and consequent rotation of lever 12. In Figure 2 the lever is shown in depressed position, immediately after the projection 11 has depressed the head 14. By such movement to the left, the lever 12 loosens the cables 23 and 24 sufficiently to allow the gates to be lowered of their own weight, as shown in Figure 2. As soon as the weight 18 has been lifted out of its normal position (lowered, in which the roller 36 presses against the weight), the force of springs 34 and 41, both acting in unison, forces the bar 35 and roller 36 to the right, under the weight 18. Figure 2 shows the position of these elements at the instant the weight has been lifted and the bar 35 is ready to move to the right. The roller, then, moves to position under the weight 18 and prevents the latter from falling, thereby retaining the cables 23 and 24 loose and preventing the gates from being lifted. When the train has passed the crossing and projection 11 strikes head 42 of lever 39, it partially rotates the latter against the force of the spring 41, pushing the bar 38 to the right and causing the bar 35 to be withdrawn from its position under the weight 18 to its normal position with the roller to the left of the weight. Hence, with the support removed from under the weight, the latter falls to its original position, again tautening the cables 23 and 24 and causing the gates to rise to the position shown in broken lines.

The springs illustrated in the drawing are shown schematically rather than practically, and obviously they may be made of solid material and of suitable design to provide the forces required for them to function as described. If the springs 34 and 41 should prove insufficient, additional springs might be located at advantageous points to augment these, for instance along the bar 38.

Obvious modifications in form and structure may be made without departing from the spirit of the invention.

I claim:

1. In combination with crossing gates rotatably mounted intermediate their length and adapted to be raised and lowered by a cable wound on a drum rotatable with the pivot of said gates, movable means mounted adjacent the track and adapted to be depressed by a train passing thereover, said cable connecting said means with said gates, said cable being normally taut and holding said gates in raised position, depression of said movable means causing loosening of said cable and causing said gates to fall into closed position by gravity, and means for keeping said gates in closed position until the train has passed the crossing.

2. In combination with crossing gates

adapted to be raised and lowered, movable means mounted adjacent the track adapted to be depressed by a train passing thereover, cables connecting said means with said gates, said cables being normally taut and holding said gates in raised position, depression of said movable means causing loosening of said cables and thereby causing said gates to fall into closed position by gravity, a weight, means connecting said weight to said movable means whereby depression of said movable means causes lifting of said weight, a slidable bar having resilient means normally urging said bar into contact with said weight, said resilient means causing said bar to slide into position under said weight when said weight has been lifted and thereby retain said cables in loosened condition and said gates in raised position.

3. In combination with crossing gates adapted to be raised and lowered, means mounted adjacent the track on one side of the crossing adapted to be operated by impact of the train for lowering the gates, said means comprising rotatable drums, said gates extending integrally from said drum, cables having their ends fixed to said drums, a lever pivotally mounted adjacent the track and adapted to be rotated by said impact, said cables being secured to said lever, a weight suspended from said lever and adapted to be lifted by said lever upon rotation of said lever, resilient means normally in contact with said weight and movable into position to support said weight in lifted position after said weight has been lifted, and means for causing said resilient means to retract from said position to permit said weight to fall and thereby raise the gates to normal position, said last-named means being located on the other side of the crossing and being adapted to be operated by impact of the train.

4. In combination with crossing gates adapted to be raised or lowered, means mounted adjacent the track on one side of the crossing adapted to be operated by impact of the train for lowering the gates, means mounted adjacent the track on the other side of the crossing adapted to be operated by impact of the train for raising the gates, a weight connected to said first-named means, said weight being lifted by said first-named means upon impact of the train with said first-named means, said second-named means comprising a movable member, a resilient member normally urging said movable member into contact with said weight and into position to support said weight from falling after said weight has been lifted, a relatively long member pivotally connected to said movable member to withdraw said movable member to normal position against the force of said resilient member, a lever pivotally mounted adjacent the track and pivotally connected to said long member,

lever being rotatable by impact of the train therewith to move said long member to withdraw said movable member to said normal position.

5 5. In combination with crossing gates rotatably mounted intermediate their length adapted to be raised and lowered by a cable wound on a drum rotatable with the pivot of said gates, movable means mounted adjacent

the track adapted to be depressed by a train passing thereover, said cable connecting said means with said gates, said cable being normally taut and holding said gates in raised position, depression of said movable means causing loosening of said cable and causing said gates to fall into closed position by gravity.

JAKOB KLEIN.
